CONTAINER FOR FLOWABLE MATERIALS OR THE LIKE

Kenneth H. Zeop, Beaverton, James C. White, Gladwin,
and Elwyn Jones, Beaverton, Mich., assignors to Koeh-
ring Company

Filed Oct. 6, 1970, Ser. No. 25,354

Term of patent 14 years

Int. Cl. D9—01

U.S. Cl. D9—1

FIG. 1 is an elevational view, partially broken away, of a container for flowable materials or the like showing our new design;

FIG. 2 is a plan view looking in the direction of the arrows 2—2 of FIG. 1 with the container being completed;

FIG. 3 is a plan view looking in the direction of the arrows 3—3 of FIG. 1 with the container being completed; and

FIG. 4 is a perspective view.

The dominant feature of the instant container design is the combination on the surface of the container of a circumferentially protruding ring and a plurality of circumferentially spaced, vertically extending fingers projecting from the upper and lower annular faces of the ring.

We claim:

The ornamental design for a container for flowable materials or the like, as shown and described.
